COMBINED CRIB AND STORAGE CABINET

Marilyn B. Harrison, Castro County, Tex.
(Rte. 2, Hart, Tex. 79043)

Filed Nov. 7, 1968, Ser. No. 14,350

Term of patent 14 years

Int. Cl. D6—01

U.S. Cl. D5—5

FIG. 1 is a front perspective view of a combined crib and storage cabinet, showing my new design as it appears with three of the bottom cabinet doors in open position and some of the drawers partially pulled out;

FIG. 2 is a top-plan view thereof as it would appear with the cabinet drawers and doors in closed position;

FIG. 3 is a front elevational view thereof as it appears with the drawers and doors in closed position; and

FIG. 4 is a rear perspective view thereof as it appears with two cabinet doors in open position and a tray in extended position.

I claim:

The ornamental design for a combined crib and storage cabinet, as shown.
